UNITED STATES PATENT OFFICE

SAMUEL I. BORDO, OF CLEVELAND, OHIO

AIR FEED MECHANISM FOR HOT AIR FURNACES

Application filed November 27, 1929. Serial No. 410,102.

My invention relates to mechanism for improving the air circulation for hot air furnaces and I do this by forcing the incoming air into the annular space between the wall 5 of the fire pot and the outer casing by suitable power means, such as a fan driven by electrical power.

It is a special object of my invention to direct the outside air into the above annular space by branch pipes connected with an outer main pipe connected with the power fan, and provide the branch pipes with upwardly-directed tubes extending just above the intensely-heated fire pot, so that the incoming air from this force feed will never be directed upon the lower portion of the fire pot.

It is a further object of my invention to form the said branch pipes of tubular sections pivoted together at their ends to permit adjustment of the curved outline of these branches to fit furnaces of different sizes, and of possible different shapes. It is a further object also to make these sections detachable to vary the ultimate length of the branches.

This invention will hereinafter be fully described in detail, particularly pointed out in the appended claims, and illustrated in the accompanying drawings, in which—

Figure 1 is a side elevation of a furnace 22 with a portion of the outer casing broken away to show the position of the structure of my improved mechanism in the intermediate space between the outer casing and fire pot;

Figure 2 is a side elevation of a single section of the feed pipe;

Figure 3 is an elevation of such a section not provided with one of the vertical tubes;

Figure 4 is a transverse section of the furnace taken in the plane indicated by the line 4—4 of Fig. 1;

Figure 5 is a side elevation of my sectional feed pipe unassembled in operative position, but having the sections swung on their pivots into alinement;

Figure 6 is a longitudinal section of two connected sections, as shown in the plane indicated by the line 6—6 of Fig. 5;

Figure 7 is a similar view of a pair of sections bent out of alinement, and

Figure 8 is a vertical section of two pivoted pipe sections taken in the plane indicated by the line 8—8 of Fig. 6.

The furnace to which my improved structure is attached, may be of any of the well known types of hot air furnaces and is designated in the drawings generally by the numeral 10, the outer casing 11 having connected therewith the usual air pipes 12, and the fire pot 13 shown as supporting the combined structure 14 having the smoke flue 16 and cleanout pipe 15.

My air feed mechanism will comprise a cold air intake pipe 17 which is designed to introduce cold air to be heated by the furnace, while in the space between the casing 11 and the fire pot 13 and thereafter forced upward into the hot air pipes 12 which lead to the various rooms to be heated. It further comprises an electric blower 18 of a conventional type whose power is obtained by suitable connections 19 carrying appropriate current from the usual power source, the incoming air entering at the opening 20 opposite the motor 21, and thence forced through the pipe 17 into a sectional distributing tubular member 22 made up of sections 23 and 24 pivoted together at 25 and extending around the fire pot from a central section 26 which receives the incoming air directly from the pipe 17.

The sections 23 and 24 are duplicated over and over in as great a number as desirable, depending partly upon the circumference of the fire pot and also upon the length of each section. The entire sectional pipe therefore, consists of two flexible members 27 and 28 extending from the section 26, and each member ending with a section 29 having a closed end 31 near the position of the furnace door 30. Each of the sections 23 and 24 will ordinarily have a small and a larger end to render it feasible to telescope the smaller end 32 of one section into the larger end 33 of the next, the two sections being held in such telescoped relation by pivot plates 34 having their ends 35 riveted to the outer wall at 35, as well shown in Fig. 8 of the drawings. These plates 34 are off-set, as shown in Figs. 2 and 3, to readily make the connection desired.

The middle section 26 will have both ends 100

of equal size to enter the sections 24 of the members 27 and 28. The length of each of the latter members may be varied by omitting or adding certain sections.

- 5 A serious defect of former air circulating attachments of this general type lay in the very general positioning of the discharge device, heretofore thought essential, in the lower portion of the space between the fire pot and the outer casing. It has often been thought advisable to direct the incoming air from the discharge opening in the attachment directly against, or closely adjacent to the highly heated lower end of the fire pot, on 10 the assumption that the incoming air would thus be very highly heated as it passed upward about the furnace and into the hot air flues. But this construction it has been found is apt to result in injury to the walls of the 15 fire pot by the expansion and contraction resulting from the forcing of the incoming cold air upon the outer surface of these walls, and the varying temperature of such fresh air as well as the varying force of the current 20 depending upon the power employed.

My improvement is therefore, especially designed to provide means for forcing the incoming air from the main discharge member into the space about the fire pot, but at points 25 above the plane to which the burning fuel extends, and at the same time preserving most of the advantages arising from positioning the main discharge member low in such air space. I have shown in these drawings a series of vertical pipes 36 which are directly attached to certain of the said pipe sections, such as those designated by the numeral 24. The lower end of these pipes will be outwardly flanged, as at 37, to provide a riveted 30 joint with the section, as shown in Fig. 2. These pipes will be of such length that their upper ends 38 which are open, will rise above the larger portion of the fire pot, so that, while the incoming air rising through these 35 pipes will be partially heated before escaping from such open ends, it will not be directed against the walls of the fire pot.

These pipes 36 may be attached to any number of the sections of my sectional distributing member 22, including the end sections 29; and if the several sections are relatively short, a given length of the main distributing member will require a larger number of sections, and fewer of the sections will need to 40 be provided with the pipes 36. For illustrative purposes only I have shown the members 27 and 28 made up of sections 23 and 24 whose alternate sections 23 support no air pipes, only the sections 24 being thus provided. In any 45 case, the pipe 17 will enter the aperture 39 in the casing and connect directly with the intermediate section 26 within the air space, and the remaining sections of the members pivoted in alternate arrangement. The entrance aperture 39 may if necessary, be posi-

tioned other than at the point directly opposite the door 30, since all of the sections will be fed by the main pipe 17, wherever it may enter the casing.

Since the several sections of my distributing member are pivoted together, the curve of such member will vary with the adjustment of the sections on each other, and at the same time carrying with them the vertical pipes 36 which will assume the appropriate position about the fire pot, as determined by the position of the main pipe 22. The members 27 and 28 need not be arranged in a pronounced curve or arc, but may evidently, be extended in arcs of small radius, or even in a substantially straight length, as shown in Fig. 5, if an elongated space is to be fitted with such attachment. The varied size and number of sections and their pivotal connection, makes possible their assemblage in old hot air furnaces as well as in new structures.

While I have shown the smaller end of each section 23 and 24, very much smaller than the other, this is to be considered merely a matter of degree, the difference in size being 50 such as to permit swinging of the sections upon their pivots, as shown in Fig. 7, but the difference in size should not be too great, so as to cause too great leakage at the joint. If however, there is a slight leakage at these 55 joints, other heavy cold air will rush in at such joints and pass upward through the pipes 36. All or only a few of the sections may be provided with such pipes, and the latter will usually be shaped of uniform size 60 throughout their length, and will ordinarily have an unobstructed orifice at their upper ends.

Operation: Assuming that the furnace 10 includes the outer casing 11 and the fire pot 13 properly assembled, and that the fire pot 13 includes a lower portion in which the burning fuel is supported and an upper portion receiving smoke and other gases as well as flames from the fuel, the two portions of the fire pot 17 ordinarily connected together as at 40, the blow pipe 17 is directed through the casing in the aperture 39, and the two members 27 and 28 of the discharge tube 22 directed outwardly and around the lower portion of the fire pot, for as long an arc as it is desired, the pipes 36 extending upwardly from the members 27 and 28 just above the plane of the connection 40, the blower 18 is driven by the motor 21 whereby the outer cold air rushes in through the opening 20 and then forced by the blower 18 into the pipe 17, and thence to the tube 22. The air in the tube 22 and in the pipes 36 is being heated by radiation from the lower portion of the fire pot 13, but no direct air current is forced against the walls of the fire pot, so that the latter will not be broken by the sudden rush of air against the intensely heated furnace walls.

The air rushing out through the orifices in

the ends 38 of the pipes 36, will be heated to a high temperature by its flow through such pipes and sections which are so closely adjacent to the fire pot, but not in contact therewith. From the ends 38, the air will then be forced upward by the heavier cold air below, and be directed to the several rooms of the dwelling by the pipes 12 of the casing. The upper portion of the fire pot 13 will of course, increase the temperature of the warm air from the pipes 36, but this part of the fire pot is not likely to be injured by such air current, since it is above the level of the burning fuel and will not be subject to extreme expansion and contraction.

The members 27 and 28 may well be supported upon standards 41, or by any means of holding such members with their attached pipes 36 in proper position in the space about the fire pot. This improved air feed mechanism meets a very serious condition which I have observed in attempting to improve the circulation of the outer air within the casing up through the carrying pipes. It is well known that the speed of the incoming air current can be increased, and has been done by devices similar to the blower 18 of my structure, but it has not been heretofore fully appreciated that forcing the air against the fire pot has wrecked such fire pots, and that the only means of correcting it in the past, seems to have been to lower the speed of such air current. My improvement therefore, enables the user to increase the incoming air current, without injury to the furnace, however great the speed of the current may be, or how intense the heat of the wall of the fire pot may become. By employing my improved structure, changes in the heat in the fuel portion of the fire pot, however sudden, as by operating the drafts, will not endanger the fire pot walls, whether the motor 21 is running at high or low speed.

Having thus described my invention, what I claim as new and desire to secure by Letters Patent, is,—

1. The combination with a furnace having an air chamber between the fire pot and the casing of the furnace, of an air tube positioned in the lower portion of said chamber, hollow pipes connected at their lower ends with such tube and having their open upper ends extending in said chamber above the level of the lower wall portion of the fire pot, and mechanism outside the said casing for forcing the outer air through an aperture in the casing into the said air tube.

2. The combination with a furnace having an air chamber between the fire pot and the outer casing of said furnace, and a sectional air tube positioned in the lower portion of said chamber of vertical hollow pipes connected at their lower ends with such tube and having their open upper ends extending in said chamber above the lower wall portion

of the fire pot, and mechanism outside the said casing for forcing outer air through an aperture in the casing into one of the sections of the said air tube.

3. The combination with a hot air furnace having an air chamber between the fire pot and an outer casing, a sectional cool air tube positioned in the lower portion of said air chamber, and vertical hollow pipes connected to certain of the sections of said tube and having their open upper ends extending in said air chamber above the lower wall portion of the fire pot, so that air from said tube and pipes will not be directed against the lower wall portion of the fire pot, of a blower device outside said casing for forcing outside air into the said sectional tube.

4. The combination with a furnace having an air chamber between the fire pot and the outer casing of the furnace, a sectional air tube positioned in the lower portion of said air chamber the sections of said air tube being connected together end to end in pivotal relation so that the tube may be positioned adjustably in an arc in said chamber, certain of said sections supporting on their upper surface vertical hollow pipes having their lower ends connected with the respective sections and their open upper ends extending above the base portion of the fire pot, so that air from either said tube nor pipes will be directed against the lower wall of said base, of a tube leading through an aperture in said casing and connecting in said chamber with one of said sections, and a blower device for forcing outside air into said casing tube.

5. The combination with a furnace having a heating chamber between an inner heating element and an outer surrounding casing, and a sectional air tube positioned in the lower portion of said chamber, of a blower device for forcing outside air into said sectional tube, and means attached to said tube for directing air therefrom upwardly in said chamber into the upper portion of the latter, but out of contact with the lower portion of said heating element.

6. The combination with a hot air furnace having a heating chamber between an inner heating element and an outer surrounding casing, and an air tube positioned in the lower portion of said chamber, of a blower device for forcing outside air into said air tube, and means attached to said tube for directing air therefrom upwardly in said chamber into the upper portion of the latter, but out of contact with the lower portion of said heating element.

7. The combination with a hot air furnace having an air chamber between the fire pot and an outer casing, a sectional cool air tube positioned in the lower portion of said air chamber, the sections of said air tube being connected together end to end in pivotal relation to permit adjustment of the tube in an

are about said fire pot, of a blower device outside said casing for forcing outer air into the said sectional tube, and spaced tubes connected at their lower ends with certain of 5 said sections and extending upwardly beyond the level of the intensely-heated base of the fire pot, for directing from the said sections air into the upper portion of said chamber, but out of contact with the said base of the 10 fire pot.

8. The combination with a hot air furnace, and its fire pot and a cool air intake pipe, of a sectional air-tube supported in the space between the said fire pot and its outer casing, 15 one of the intermediate sections being connected with said intake pipe, and the end sections having closed outer ends, a plurality of vertical pipes having their lower ends attached to certain of said sections, and their 20 open upper ends extending above the level of the most intensely-heated portion of the fire pot, whereby the air in said pipes will be heated by radiation from the base of the fire pot, but will not be directed against the wall 25 of the latter, and a blower arranged for connection with the receiving end of said intake pipe.

9. The combination with a hot air furnace having a heating chamber between an inner heating element and an outer surrounding casing, and a sectional air tube positioned in the lower portion of said chamber, tubular mechanism outside the said casing leading through an aperture in the casing into one of 30 the air tube sections, and means attached to certain of said sections for directing air therefrom upwardly into the upper portion of said chamber, but out of contact with the lower portion of the said heating element.

40 In witness whereof I have hereunto set my hand this 26th day of November, A. D. 1929.
A. D. 1929.

SAMUEL I. BORDO.
